UNITED STATES PATENT OFFICE.

JOHN REID, OF NEW YORK, N. Y.

OIL-BURNING-FURNACE CONSTRUCTION.

1,321,555.

Specification of Letters Patent.

Patented Nov. 11, 1919.

Application filed August 14, 1919. Serial No. 317,538.

To all whom it may concern:

Be it known that I, JOHN REID, a subject of the King of Great Britain, and residing at 30 Church street, in the city of New York, in the State of New York, in the United States of America, have invented a new and useful Oil-Burning-Furnace Construction, of which the following is the specification.

10 The invention relates to oil burning furnace construction as described in the present specification and illustrated in the accompanying drawings that form part of the same.

15 The invention consists essentially in the novel means of distributing the draft air from the heaters to and through the furnace fronts for mixing purposes in furthering the combustion of the oil.

20 The objects of the invention are to facilitate the consumption of the oil and thereby economize in the quantity of oil used; to avoid uneven temperatures from poor mixtures and thereby maintain the steam pres-

25 sures in one or a plurality of boilers; to facilitate shipping and assembling; to effect quick replacements and repairs and thus eliminate delays and accidents particularly in marine installations; to furnish parts

30 built on standard patterns; and generally to provide an efficient, durable and serviceable construction for the purposes aforesaid.

In the drawings, Figure 1 is an elevation of the back plate, showing the intermediate parts and walls in section and valves full.

35 Fig. 2 is a vertical sectional view of the furnace front.

Fig. 3 is a diagrammatic view, showing the course of the air from the preferred 40 form of air heaters.

Fig. 4 is a detail of the inner and central air wall.

Fig. 5 is a horizontal sectional view on the line of the air valves and cover plate.

45 Like numerals of reference indicate corresponding parts in each figure.

Referring to the drawings, the frame of the front is formed with the front plate 1 having the upper opening 2 at or near the 50 center and the lower opening 3, both openings being for accessibility to the interior of the front and the lower opening being also for natural draft purposes when required. The back plate 4 of the frame has

55 a central circular opening 5 for the burner in which a Venturi tube 6 or other air con-

centrating device is situated. One intermediate part of the frame is the air pocket wall 7 at its lower end preferably following the shape of the back plate 4, and as it rises 60 converges slightly to the vertical end portions 8 above the central opening 5. Another intermediate part is the division wall 9 forming a deflecting plate in the lower central portion of the air pocket and another 65 intermediate part is the deflecting hood 10 centrally arranged of the plates. All of the intermediate parts described are rigid with the front and back plates and preferably are cast in one piece therewith, though it is 70 not necessary that they should be.

The inner central air wall 11 is preferably a separate part from the frame and may be inserted from the back in the central opening 5. The wall 11 which is circular at its 75 inner end and at the bottom slopes up to the straight lower edge 12, forms a tube or casting surrounding the burner 13 and in the top has the air ports 14 and in the bottom the air port 15, therefore the air reaches the 80 vapor from the burner at all sides through the Venturi tube or other suitable aperture.

The cover plate 16 is beneath the deflecting hood 10 and is recessed at 17 to make room for the valve operating mechanism. 85 The flanges 18 and 19 at the edges of the cover 16 abut the back and front plates respectively and are suitably secured thereto and the end flanges 20 and 21 form bearings for the valve shaft 22 carrying the valves 90 23 and 24 and closing the spaces between the cover plate 16 and the vertical end portions 8 of the air pocket wall, thereby completing the closure of the air pocket.

The valves are shown as operated by the 95 crank handle 25, the spindle 26 of which carries the crank 27 pivotally joined to the connecting rod 28, the latter being pivotally connected to the crank 29 fixedly mounted on the shaft 22.

100 The preferable arrangement of heaters for the draft air is shown in Fig. 3 and by this construction greater efficiency is obtained mainly because in a battery of furnaces usual to marine installations, each furnace 105 receives its proper proportion of air, though the front as described is certainly operable in a battery of furnace fronts with the single type of air heater or with any kind of air heater suitable to the forced draft style 110 in furnace construction.

In Fig. 3, the numerals 30, 31 and 32 indi-

cate air heaters discharging air at 33 on the one side from the heater chamber 30 and 34 on the opposite side from the heater chamber 32, while the central heater chamber discharges air from both ends at 35 and 36.

The air passage 37 leads from the discharge 33 to the furnace front 38 and the passage 39 leads from the discharge 34 to the furnace front 40, while the passages 41 and 42 lead from the discharges 35 and 36 to the furnace front 43. The course of the air, which flows by forced draft through the heater chambers, after it leaves the passage will now be briefly described in concluding this description.

The valves, being opened in the manner described or by any other simple valve gear, the air rushes into the air pocket between the front and back plates and before actually entering is deflected by the deflecting hood and thus directed to the ports closed by the valves. A quantity of the air entering the pocket flows through the upper openings in the inner central air wall and the remainder flows into the lower portion of the pocket and meets the division wall or deflecting plate and by it is turned upwardly into the lower port of the central inner air wall and as the latter is shaped to converge to a narrower front end, the whole tendency of the air flow is toward the back plate and consequently to and through the Venturi tube or other opening from where it is distributed evenly and becomes laden with oil vapor and burnt in the well known manner of oil burning furnaces.

Various changes may be made in the details of the construction without departing from the spirit of the invention, and so long as these changes are within the scope of the claims for novelty following, the protection accorded shall not be invalidated.

What I claim is:—

1. In oil burning furnace construction, a furnace front comprising a frame having front and back plates and an air pocket therebetween having ports and deflecting plates, a burner, an inner air wall surrounding said burner and having ports there-through suitably distributed, valves closing said air pocket ports, and means for directing air under pressure to said pocket.

2. In oil burning furnace construction, a furnace front having front and back plates and a pocket formed by a wall extending downwardly from the upper portion and around and across the lower end of said

plates and having ports at the upper end, valves closing said ports, a central deflecting plate in the lower portion of said pocket, 60 a burner, an inner air wall having upper and lower ports and forming a casing around the burner, and means for feeding air to said pocket.

3. In oil burning furnace construction, a furnace front having front and back plates spaced by rigid walls, the main wall extending from the upper portion around the lower portion of the front, a deflecting wall extending upwardly from the center of said 70 wall in the lower portion and a deflecting hood at the upper end centrally between the extremities of said main wall, valves pivotally mounted at either side adjacent to the upper ends of said main wall, a cover plate 75 therebetween, a valve gear, a burner and an inner central air wall forming a casing around said burner and having ports there-through suitably distributed.

4. In oil burning furnace construction, a furnace front having a removable central substantially tubular wall with air ports and converging toward its front end and back and front plates supporting said wall, a fixed air pocket wall partially surrounding 85 said tubular wall, a division wall from said pocket centrally at the lower part thereof and terminating at the lower port of said tubular wall, a cover plate and valves closing in the upper end of said pocket, a burner, 90 and means for operating said valves.

5. In oil burning furnace construction, a furnace front forming between its front and back plates an air pocket surrounding an inner air wall having ports suitably distributed, a burner, and an individual air heater chamber having a discharge passage from each end leading to each side of the furnace front.

6. In oil burning furnace construction, a central furnace front forming between its front and back plates an air pocket surrounding an inner wall having air ports, wing furnace fronts arranged on either side of said central front and having air pockets 105 between the front and back plates surrounding inner air walls having air ports, a central air heater chamber feeding air to said central furnace from each end and wing heater chambers, each having a passage to 110 the wing furnace fronts respectively.

Signed at the city of New York this 2nd day of Aug., 1919.

JOHN REID.
